UNITED STATES PATENT OFFICE.

JOHN B. BAXTER, OF WATERVLIET, NEW YORK, ASSIGNOR TO COVERT MANUFACTURING COMPANY, OF WATERVLIET, NEW YORK.

SNAP-HOOK.

1,044,975.

Specification of Letters Patent. Patented Nov. 19, 1912.

Application filed January 24, 1912. Serial No. 673,086.

To all whom it may concern:

Be it known that I, JOHN B. BAXTER, a citizen of the United States, residing at Watervliet, in the county of Albany and State of New York, have invented certain new and useful Improvements in Snap-Hooks, of which the following is a specification, reference being had therein to the accompanying drawing.

10 This invention relates to snap hooks and has for its object the provision of certain improved details, as will hereinafter appear, tending to perfect a device of the character stated.

15 What may be styled the conventional snap now in use comprises a casting consisting of a shank having at one end a nose or hook and at its other end an attaching eye for a strap or the like, in combination with a 20 spring tongue secured to the shank, usually in a pocket therein, at a point near the eye and engaging at its free end beneath the end portion of the nose. In such a construction the end of the nose is exposed 25 above the tongue and affords an obstruction beneath which the hair of the tail or mane may catch and dislodge the tongue inwardly away from the nose, thus opening the snap and permitting escape of the ring expected 30 to be held thereby, or on the other hand by an edgewise motion of the tongue outwardly beyond the sides of the nose and thus freeing the tongue from the latter.

My present invention embraces a construction 35 wherein the objectionable characteristics of the conventional snap referred to are eliminated and the advantages of the combination of an offset tongue and a recessed nose, together with other advantages, are 40 accomplished in a single device simple in construction, conveniently and cheaply manufactured.

To the end stated, the preferred embodiment 45 of the invention comprises a snap hook having a nose, the extremity of which is furcated longitudinally of the free portion of the nose, the terminals of the extensions or arms of the furcated portion depending inwardly toward the body or shank of the 50 hook, and a spring tongue secured at one end to the body or shank and at its free end having an intermediate offset portion passing through the notch constituted by the furcation so that the extreme end of the

tongue will underlie the nose, while the 55 outer surface of the major portion of the tongue beyond the offset will be coincident or flush with the outer surface of the nose. The result is three advantages, to wit, first the elimination of external projections or 60 crevices adapted to catch the hair of the animal, second the prevention of edgewise or lateral play of the tongue relative to the nose, and third, the enabling of a substantial 65 inward movement or play of the tongue under abnormal engagement with exterior objects within the confines of the inward projections on the nose, without opening the snap for the escape of the ring or device fastened in place by the snap. 70

Another embodiment of the invention comprises a snap hook wherein the nose, as distinguished from the furcated idea above suggested, is provided with inwardly projecting side flanges adapted to coöperate 75 with the offset tongue referred to.

The invention also includes a special construction of tongue, and its combination with a snap body having a pocket, above referred to, wherein the tongue is bent or 80 offset near its secured end so as to be projected at its free end in a plane in line with the top wall of the pocket for purposes as will hereinafter appear.

The embodiments of the invention to 85 which I have alluded are illustrated in the accompanying drawings forming part hereof wherein,

Figure 1 is a side elevation of the preferred snap, Fig. 2 is a plan view, Fig. 3 a longitudinal vertical sectional view of Fig. 1, Fig. 4 is a transverse sectional view through the spring tongue and shank of the hook looking in the direction of the nose, and Figs. 5, 6 and 7 are respectively a side elevation, 90 longitudinal section, and transverse section of the second form of snap made in keeping with the invention.

Referring more specifically to the drawings wherein like reference characters designate corresponding parts in the several views, A represents the shank or body of the usual casting having at one end an eye or loop B for the reception of a strap or the like, and at its other end the nose or lip C 100 flattened at its return bend or free portion which lies substantially parallel to the shank, represented at D, and E is the spring

tongue secured in any convenient or desirable manner at its inner end in the pocket *a* of the shank *A* adjoining the ring or loop *B*.

In Figs. 1 to 4 inclusive, the extremity 5 of the nose or lip *C* is furcated as at *F* to constitute an end edge or wall *G*, and side extensions *H* constituting prolongations of the nose. The extensions are also carried inwardly, as at *I*, toward the shank 10 *A*, a substantial distance to constitute a guideway therebetween at right angles to the plane of the nose or lip, as shown at *J*. The end of the spring tongue is provided with an intermediate offset portion *K* adapted to pass through the furcated extremity of the nose adjoining the inner wall or edge referred to and between the extensions or arms, the extreme end of the tongue 15 *L* beyond the offset, underlying and engaging the nose to close the snap. It will be observed that the outer or exposed surfaces of the nose and tongue are substantially flush to afford a continuously smooth surface; also that the passing of the tongue 20 through the furcation prevents lateral displacement of the tongue when in its normal position; and further by reason of the extended guidance afforded by the inward extensions of the arms for the offset portion 25 of the tongue, the latter has quite a substantial inward play or movement, while at the same time maintaining a closed relation between the nose and tongue to prevent the escape of the ring or other device from the 30 hook.

In Figs. 5 to 7 inclusive, as distinguished from the furcation *F* in the nose or lip *C* of the preceding figures, the nose or lip, in this instance, is flattened laterally as shown 35 and provided with inwardly directed side flanges *M* adapted to receive therebetween the offset free end of the spring tongue. These flanges, and also the extensions *I* are preferably inclined slightly to assist in centering the end of the spring tongue in the 40 recess under the end of the nose of the tongue, and they are also inclined upwardly and inwardly along their inner edges *N* to merge into the curved inner surface *O* of the hook, and rounded at their corners *P* to offer as little obstruction as possible to the ring or other device fastened within the 45 snap.

In both embodiments of the invention 50 herein set forth what might be styled the middle portion of the spring tongue is offset in an outward direction, as at *Q*, which it will be observed is at its point of emergence from the pocket *a* of the shank. The 55 offset is for the purpose of elevating the free end of the spring tongue, so that its exposed surface is not only flush with the exposed surface of the nose, but also in line or flush with the outer surface of the top 60 or upper wall *a'* of the pocket, thus afford-

ing a smooth and pleasing appearance, rendering the snap, as nearly as possible, devoid of external projections, and permitting the nose to be raised somewhat from its position now in use to the end that, notwithstanding the inwardly projecting flanges or extensions on the nose, the space within the snap hook will be preserved in size sufficient to accommodate what are known as the standard large rings, which is a feature of substantial importance in some styles of 75 snaps. Further than this, the upward curve or incline of the spring tongue, constituted by the offset referred to, where the spring leaves the pocket, keeps the tongue away 80 from the sides of the snap adjoining the pocket when the spring is pressed inwardly, while preserving the proper plane or angularity of the spring with the hook, similar to the ordinary straight spring, to give the 85 spring in this instance the proper tension for successful and satisfactory service.

In fact, by elevating the free portion of the tongue incident to the so-called middle offset portion, the spring is brought more 90 directly in approximately horizontal alignment with the nozzle or hook of the snap than is the case when the spring projects straight out from beneath the top wall of the pocket in an inclined upward line to a 95 point beneath the nose.

While I have herein disclosed specific embodiments of the invention, it will be understood by persons skilled in the art that the invention is capable of still other embodiments not necessary to be herein illustrated and described, but within the scope of the 100 appended claims.

I claim:

1. A snap hook of the character described 105 comprising a shank portion provided with a nose furcated longitudinally at its extremity, the arms constituted by the furcation constituting prolongations of the nose and extending inwardly toward the shank 110 portion, and a spring tongue secured at one end to the shank and at its opposite free end engaging beneath the nose, an intermediate portion of the tongue being offset to pass through the way constituted by the extensions on the nose so that the tongue is prevented from edgewise displacement and the exposed surfaces of the nose and tongue made substantially flush with each other, substantially as described.

2. A snap hook of the character described 120 comprising a shank portion provided with a nose furcated longitudinally at its extremity, the arms of the furcated portion constituting prolongations of the nose and extending inwardly toward the shank portion, a spring tongue secured at one end to the shank engaging beneath the nose, said spring tongue passing through the way constituted 125 by the extensions on the nose so that the 130

tongue is prevented from edgewise displacement, substantially as described.

3. A snap hook of the character described comprising a shank portion having a hollow inner end provided with a top wall and an outwardly opening mouth, the shank portion also having a nose at its outer end terminating in a pair of inwardly directed separated extensions opening toward the intermediate portion of the shank and constituting a guideway between said extensions, and an approximately U-shaped spring tongue having its bent connecting portion seated in and its inner end secured within the pocket at the inner end of the shank, the free portion of the tongue member emerging outwardly through the mouth of the pocket and engaging beneath the nose, an elongated intermediate part of said free portion of the tongue being offset outwardly to provide

shoulders at the opposite ends of said intermediate part one adapted to confront the end of the nose and the other to confront the forward edge of the top wall of the pocket so that the intermediate portion at its inner end will be substantially flush with the exposed surface of the top wall of the pocket and at its outer end substantially flush with the outer surface of the nose with the extreme end of the free portion of the tongue passing through the guideway between the extensions and bearing against the under surface of the nose. 25 30

In testimony whereof I affix my signature in presence of two witnesses.

JOHN B. BAXTER.
